TAKE-OFF FOR GRID TRIMMING PRESSES

Alfred E. Willard, East Cleveland, Ohio, assignor
to Willard Storage Battery Company, Cleve-
land, Ohio, a corporation of West Virginia

Application June 3, 1932, Serial No. 615,253

14 Claims. (Cl. 193—43)

This invention relates to an improved take-off for grid trimming presses, and the like. The grids used in storage batteries are made by casting a lead alloy in molds. As is usual in casting operations, there is excess metal on the casting at the gate and other points, left there for casting or process reasons. The customary way to remove this gate and excess metal is by punching or shearing it off in punch or trimming presses, using dies properly designed for this purpose. Trimming or shearing off of excess metal is a common operation in many kinds of metal working, and in handling the harder metals the pieces of work after they are trimmed may be allowed to slide or drop from the trimming dies after being ejected, and be deposited in tote boxes or other receptacles without suffering damage. This is not the case with storage battery grids, as they are not only cast from a metal which is unusually heavy and soft, but they are little more than lacework in construction, and even a slight fall or bump can bend them out of shape or break the small ribs and bars composing them, and thus render the grids mere scrap. The grid take-off of the present invention comprises a novel piece of apparatus over which the twin grids, when ejected from the machine, are adapted to slide by gravity and upon which they arrange themselves in vertical planes upon supporting rails from which they hang by their lugs, the slide being so constructed as to work in conjunction with the force of gravity to straighten up any grids which may start down the slide more or less obliquely. By thus maintaining the moving grids straight with respect to the slide or the side guides thereof, they cannot become jammed and hence move in orderly relation onto the track provided therefor, when they can be conveniently grasped in groups or stacks by an operator and removed.

The principal object of the invention is the provision of a grid take-off which shall function to keep the grids straight as they move along the take-off, and thereby prevent damage to the grids and interruption to the operation of the machine with which the take-off is used.

Another object is the provision of a take-off of such character that the grids collected thereupon shall be supported in orderly arrangement side

50 by side so as to facilitate their removal.

Other objects and features of novelty will appear as I proceed with the description of that embodiment of the invention which, for the purposes of the present application, I have illustrated in the accompanying drawings, in which

Figure 1 is a side elevational view of a grid take-off embodying the invention, shown operatively associated with a grid trimming press, a fragment only of which is illustrated.

Fig. 2 is a plan view of the same.

Fig. 3 is a vertical cross sectional view taken substantially on the line 3—3 of Fig. 1, showing the grid collecting or stacking portion of the take-off.

Fig. 4 is a cross sectional view taken substantially on the line 4—4 of Fig. 1.

In the drawings I have indicated at 10 the bed of a trimming press upon which is mounted a die 11 having an inclined face and provided with a pair of upwardly extending grid locating and holding pins 12. The die 11 is adapted to support a twin grid, indicated in Figs. 1 and 2 by the reference character A. In Fig. 1 the excess metal across the top of the twin grid is shown at A'. The lugs of the grid, shown at A² and A³, engage with the pins 12 to thereby accurately position and support the grid upon the inclined face of the die 11.

13 is a movable die member, which is adapted to grip the grid A when a cut is to be made. In the operation of the trimming machine, after the grid is placed in proper position by the operator, he releases a control (not shown) which causes die 13 to descend and engage the grid, holding it firmly against die 11, after which a knife 14 travels downwardly, severing the excess metal A' from the grid. Immediately thereafter one or more knock-out pins rise and kick the trimmed grid off the pins 12, permitting it to slide downwardly over the face of the die 11. Any convenient knock-out means may be employed rather than that which is diagrammatically illustrated in Fig. 1, where the pins 15 are arranged to be raised at the proper time in the cycle of operations of the press, that is just following the upward travel of the die 13 and knife 14, by means of a cam or cams 16 on a shaft 17, the latter making one revolution for each cycle of movement of the press. It will be understood also that in place of knock-out means, the pins 12 could be readily actuated to be withdrawn at the proper time, but the knock-out means is somewhat to be preferred in that it imparts a positive impulse to start the downward travel of the grid.

A pair of angle brackets 18 are attached to the machine bed 10 by means of screws 19 or the like. In these brackets there are slots 20 which receive adjustably bolts 21 by means of which a transverse angle iron brace 22 is supported.

The brace 22 serves to support the upper ends of the track members of the take-off, of which there are three in this case. The two outer track members 23 are longer than the intermediate track member 24, and are connected to the brace near the outer ends of the latter by bolt and slot connections 26 and 27, by means of which the track members may be spaced different distances to conform to the dimensions of the particular twin grids being handled. The track member 24 is supported upon the brace 22 half way between the outer track members 23 by any removable fastening, as for instance by slot and screw connections 28 and 29 which render the mounting adjustable. Near their outer ends the track members 23 are connected by an angle brace 25, bolt and slot connections 30 and 31 being employed in order to permit different spacing of the track members. The brace 25 extends outwardly considerably beyond the track members 23, and at its extremities is attached to diagonally arranged braces 32 that are provided at their forward ends with a series of holes 33 for selective attachment to the machine frame 34 by means of screws 35. By means of this adjustment the angle of inclination of the take-off may be varied to some extent.

Each of the outer track members 23 is provided with an integral ledge 36 which extends the full length of the track member. Together these ledges form a continuous slide for the body portions of the grids, being located at their forward ends close to and slightly beneath the level of the die 11, so as to receive grids readily from the die when the knock-out operates. Part way down the take-off these ledges are provided with some means for temporarily increasing the friction presented to the traveling grids. In the case here illustrated this means takes the form of humps 37 in the ledges, which humps have a gradual increase in height, as compared with the straight part of the ledges thereabove, until the peak of the hump is reached, after which the descent is likewise gradual. On account of the low strength-weight ratio of the alloy used in battery grids it is essential to support twin grids in the middle as well as at the ends. Hence the intermediate track member 24 is provided, and has a slide surface 38 conforming precisely to the slide surfaces of the ledges 36 on the outer track members, including a hump 39 of the same contour and height as the humps 37.

Upon the outer track members there are side rails 40 spaced above the ledges 36 a more or less uniform distance as far down the take-off as the peaks of the humps 37, after which these rails continue in a straight lateral direction at a slight downward inclination. The tops of the rails 40 constitute a track for the support of the lugs A² and A³ of the grids, and the inner sides of the rails form guides for the side edges of the grids, as shown particularly in Fig. 4. In addition to the guide surfaces afforded by the inner walls of the side rails 40, I provide guide plates 41 and 42 flared outwardly at their upper ends for the guiding of the grid lugs. The plate 41 is attached directly to the outer wall of the corresponding rail 40, but the plate 42 is attached to its rail through spacing washers 43 on account of the greater length of the lugs A².

On the lower and outer straight portions of the ledges 36 I mount a transverse bar 44 which is provided at its ends with grooves to receive the ledges and with adjustable plates 45, by means of which the depth of the grooves may be regulated

so as to provide a nice sliding fit. On this bar I secure an upstanding transverse plate 46 which is adapted to engage the outermost one of the grids supported upon the rails 40. In order to insure the travel of the bar 44 and plate 46 always parallel to themselves and at right angles to the track members 23, I mount guide rods 47 in the bar. These rods extend a considerable distance toward the trimming press, and are guided by a transverse bar 48 having holes therein for the reception of the rods, the bar 48 being bolted to the outer end of the intermediate track member 44. The bar 44 with its plate 46 is urged inwardly, or toward the press, by tensile springs 49 attached at their ends to the plate 46 and to the bar 48.

In the drawings I have indicated in dotted lines a number of twin grids in various positions along the take-off. In addition to the grid A, I have shown a grid B in Fig. 4 at the start of its movement on the take-off. At C in Fig. 1 there is a grid in engagement with the hump 37 of the slide which effects the straightening of any grids which tend to travel in oblique position. The grid shown at D is in the process of being changed from a reclining posture to a vertical one. The grid position E and the several grids at F indicate the limits of a stack of grids collected in the take-off in front of the plate 46.

Operation. When a grid is delivered from the trimming press, the lower edge of its body moves onto the slide provided by the ledges 36 and the rail 38. A moment later the lugs A² and A³ move onto a track consisting of the side rails 40, and are centered by the plates 42 and 41 respectively. The first part of the travel of the grid down the take-off is upon straight surfaces both as to the ledges 36 and the rails 40. If at the end of this portion of its travel the grid is more or less askew, the forward end of the body portion will encounter the hump 37 at that side of the apparatus first, which will present increased friction to that end of the grid, slowing it up more or less until the opposite end of the grid swings around to bring the two ends into transverse alignment. The rails 40 also have slight humps therein, which afford more or less assistance to the humps 37 in this straightening operation. The guide surfaces on the inner walls of the rails 40 also help to bring the grids into straightened relation to the slide.

It will be noted that the use of humps in the slide as a friction increasing means is particularly suited to the purpose, inasmuch as it is possible to grade the friction increase to a nicety and to make the increase progressive from the beginning to the peak of the hump, which is also advantageous as tending to prevent sudden swinging of the oblique grid, which might carry the other end of the grid too far forward and produce obliqueness in the opposite direction. By the time the grid has reached the position indicated by C in Fig. 1 any obliqueness in its position has been corrected.

Thereafter the lugs of the grid travel forward on a straight line, and the lower edge of the grid moving along the descending side of the hump in the slide swings gradually into vertical position. The outer straight portions of the ledges 36 are spaced far enough below the rails 40, as will be evident from Fig. 1, to clear the lower edges of the grids. If the take-off is empty of grids at the time, the bar 44 and plate 46 will be in a forward position somewhat to the rear of the indicated position of grid E in the drawings. The grid in question will then

slide down the rails 40, which are set at a slight inclination, until it is brought to a stop by the plate 46. Successive grids are stacked up in front of the plate 46 and the stack, as it is increased by the addition of further grids, will travel slowly downward upon the rails 40 in opposition to the springs 49 until the operator withdraws some or all of them and places them upon a truck or other means of conveying them to the location where the next operation upon the grids is to be performed. The plate 46 keeps the grids in proper transverse arrangement with respect to the rails 40, so that there is no danger of their acquiring such an angle with respect to rails 40 as to cause the lugs of the grids to lose their hold upon the rails.

While the use of humps in the slide is the preferred means of subjecting the grids to friction for straightening purposes, it will be understood that other friction increasing means may be employed without departing from the spirit of the invention. It will also be understood that other changes in the apparatus may be resorted to within the scope of the claims, for instance the intermediate track member 24 might be omitted where the grids are not very broad or where articles made of some material having a greater strength-weight ratio than lead alloy are being handled. Also, the slide, including the friction increasing hump, could be continuous all the way across its width instead of being formed upon track members as is the case herein illustrated.

Having thus described my invention, I claim:

1. A take-off for flat articles adapted to be operatively associated with the delivery end of a machine from which the flat articles are delivered approximately flatwise in a lateral direction, said take-off comprising an inclined slide having an upwardly extending transverse hump therein, whereby articles moving obliquely down the slide above the hump are straightened up by the hump and caused to move thereafter in squared relation to their path of travel.

2. A take-off for flat articles adapted to be operatively associated with the delivery end of a machine from which the flat articles are delivered approximately flatwise in a lateral direction, said take-off comprising an inclined slide, said slide having means located intermediate its ends adapted to function equally upon the portions of the article traveling upon opposite sides of the center line of the slide for increasing friction between the slide and the article moving thereover, said means being adapted to present increased friction to the advanced front corner of an obliquely traveling article until the retarded front corner swings to transverse alignment.

3. A take-off for flat articles adapted to be operatively associated with the delivery end of a machine from which the flat articles are delivered approximately flatwise in a lateral direction, said take-off comprising an inclined slide having a portion of its length presenting increasingly greater friction to the article as it travels down the slide, whereby friction tending to retard an obliquely moving article is greatest on its furthest advanced corner.

4. A take-off for flat articles adapted to be operatively associated with the delivery end of a machine from which the flat articles are delivered approximately flatwise in a lateral direction, said take-off comprising an inclined slide, a portion of the length of said slide being adapted to present greater friction than the remaining

portions of the slide, whereby the furthest advanced corner of an obliquely moving article strikes the increased friction zone first and thereby receives a retarding effect tending to straighten the article, and side guides for said slide.

80

5. A take-off for flat articles adapted to be operatively associated with the delivery end of a machine from which the flat articles are delivered approximately flatwise in a lateral direction, said take-off comprising an inclined slide having increased friction areas therein at opposite sides thereof and in transverse alignment, whereby the speed of travel of an article over the slide is checked by said areas and whereby the increased friction area first encountered tends to retard the movement of that end of the article until the opposite end encounters the other increased friction area.

85

6. A take-off for twin grids adapted to be associated with the delivery end of the trimming press or the like, comprising an inclined slide, inclined side rails upon which the lugs of a twin grid are adapted to slide while the body of the grid moves flatwise over said inclined slide, a transverse zone of said slide being adapted to present greater friction than the remaining portions of the slide, whereby the furthest advanced corner of an obliquely moving grid strikes the said zone first and thereby receives a retarding effect tending to straighten the grid.

90

7. A take-off for twin grids adapted to be associated with the delivery end of a trimming press or the like, comprising an inclined slide, inclined side rails upon which the lugs of a twin grid are adapted to slide while the body of the grid moves over said inclined slide, said take-off having increased friction areas therein at opposite sides thereof in transverse alignment, whereby the speed of travel of a grid along the rails and slide is checked by said areas, and the increased friction area first encountered tends to retard the movement of that end of the grid until the opposite end encounters the other increased friction area.

105

8. A take-off for twin grids adapted to be associated with the delivery end of a trimming press or the like, comprising an inclined slide, inclined side rails upon which the lugs of a twin grid are adapted to slide while the body of the grid moves over said inclined slide, said take-off having means located intermediate its ends and adapted to function equally upon the two ends of the grids, for increasing friction between the take-off and the grids, said means being adapted to present increased friction to the advanced end of an obliquely traveling grid before presenting increased friction to the retarded end thereof.

110

9. A take-off for twin grids adapted to be associated with the delivery end of a trimming press or the like, comprising an inclined slide, inclined side rails upon which the lugs of a twin grid are adapted to slide while the body of the grid moves flatwise over said inclined slide, said take-off having a transverse zone which presents increasingly greater friction to a grid as it travels down the take-off, whereby friction tending to retard an obliquely moving grid is greatest on its furthest advanced end and is equalized when the grid is traveling downward in squared relation to the side rails.

115

10. A take-off for twin grids adapted to be associated with the delivery end of a trimming press or the like, comprising an inclined slide, inclined side rails upon which the lugs of a twin grid are adapted to slide while the body of the grid moves

120

125

130

135

140

145

150

flatwise over said inclined slide, said slide having an upwardly extending transverse hump therein, whereby grids moving obliquely down the slide above the hump are straightened up by the hump and caused to travel thereafter in squared relation to said side rails.

11. A take-off for twin grids adapted to be associated with the delivery end of a trimming press or the like, comprising an inclined slide, inclined side rails upon which the lugs of a twin grid are adapted to slide while the body of the grid moves flatwise over said inclined slide, a transverse zone of said slide comprising means for presenting greater friction than the remaining portions of the slide, whereby the furthest advanced corner of an obliquely moving grid strikes the said zone first and thereby receives a retarding effect tending to straighten the grid, the lower ends of the rails and slide being separated sufficiently to leave the grids hanging vertically from the rails by their lugs.

12. A take-off for twin grids adapted to be associated with the delivery end of a trimming press or the like, comprising an inclined slide, inclined side rails upon which the lugs of a twin grid are adapted to slide while the body of the grid moves over said inclined slide, a transverse zone of said slide comprising means for presenting greater friction than the remaining portions of the slide,

whereby the furthest advanced corner of an obliquely moving grid strikes the said zone first and thereby receives a retarding effect tending to straighten the grid, the lower end of the slide diverging gradually downward away from the rails in order that the grids may be caused to assume vertical position gradually as they move along the take-off away from said friction zone.

13. A take-off for storage battery grids comprising separate inclined tracks for the lugs and body of the grids adapted to support the grids flatwise, at least one of said tracks being provided with means affording a transverse high friction zone adapted to present suddenly increased friction to the travel of a grid.

14. A take-off for twin storage battery grids, comprising a track having a pair of spaced inclined rails for engagement with the lugs of the grids, a second inclined track positioned for engagement with the lower edges of the grids, said second track being arranged at a level near the level of the first track, whereby the grids are supported during travel approximately flatwise, at least one of said tracks being provided with means affording a transverse high friction zone adapted to present suddenly increased friction to the travel of a grid thereover.

15. A take-off for twin storage battery grids comprising a track having a pair of spaced inclined rails for engagement with the lugs of the grids, a second inclined track positioned for engagement with the lower edges of the grids, said second track being arranged at a level near the level of the first track, whereby the grids are supported during travel approximately flatwise, at least one of said tracks being provided with means affording a transverse high friction zone adapted to present suddenly increased friction to the travel of a grid thereover.
